CLAIM

I claim the ornamental design for a bird feeder, as shown and described.

DESCRIPTION

FIG. 1 is a perspective view of a first embodiment of the bird feeder of my design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof;

FIG. 8 is a perspective view of a second embodiment of the bird feeder of my design;

FIG. 9 is a front elevational view thereof;

FIG. 10 is a top plan view thereof;

FIG. 11 is a bottom plan view thereof;

FIG. 12 is a left side elevational view thereof;

FIG. 13 is a right side elevational view thereof; and,

FIG. 14 is a rear elevational view thereof.

The broken line showing of a bird and a citrus fruit half in FIGS. 1 and 8, illustratively depicts environment and exemplary in-use elements, and forms no part of the design claim.
